AIR FRESHENER OR SIMILAR ITEM

Georg Schimanski, Rummenohl, Germany, assignor to
Global-Werk GmbH, Neuburg an der Donau, Germany

Filed Aug. 20, 1974, Ser. No. 498,882

Claims priority, application Germany May 2, 1974

Term of patent 14 years

Int. Cl. D23—04

U.S. Cl. D23—150

Fig.1

Fig. 2

Fig. 3

Fig.4

Fig.5

FIG. 1 is a partially exploded perspective view of an air freshener or similar item showing my new design;

FIG. 2 is an exploded front elevational view;

FIG. 3 is a partial sectional view with the cap omitted for ease of illustration;

FIG. 4 is a plan view taken along line 4—4 of FIG. 2; and

FIG. 5 is a plan view taken along line 5—5 of FIG. 2.

I claim:

The ornamental design for an air freshener or similar item, as shown and described.
